UNITED STATES PATENT OFFICE.

EMIL ROTH, OF VIENNA, AUSTRIA-HUNGARY.

AUTOMATICALLY-COCKING FIREARM.

SPECIFICATION forming part of Letters Patent No. 727,453, dated May 5, 1903.

Application filed July 19, 1902. Serial No. 116,273. (No model.)

To all whom it may concern:

Be it known that I, EMIL ROTH, a subject of the Emperor of Austria-Hungary, and a resident of Vienna, Austria-Hungary, have invented a new and useful Self-Cocking Trigger Mechanism, of which the following is a description.

The present invention relates to self-cocking trigger mechanism; and its object is to render the same applicable to automatic firearms of all classes and more particularly to weapons having firing-pins.

In order to render the present specification easily intelligible, reference is had to the accompanying drawings, in which similar letters of reference denote similar parts throughout the several views.

Figure 1 is a sectional elevation of the parts of the lock of an automatic firearm necessary for the proper explanation of the invention, the parts being in their position of rest before the trigger is pulled. Fig. 2 is a similar view showing the position of the parts after the trigger has been drawn back and at the moment of release of the firing-pin, and Fig. 3 is a similar view showing the position of the parts when the weapon hangs fire.

The invention is applicable to any weapon having a self-cocking mechanism—revolver, pistol, rifle, or other firearm.

According to the present invention the breech-bolt *e* carries the firing-pin *d*, having its spring in the ordinary form of construction. The trigger *a* is pivotally mounted at *a'* in the well-known manner and provided with the usual trigger-spring. The sear *b* is pivotally mounted at *b'* and carries the spring-pressed pawl *c*, contacting with the trigger *a*, and the arm *b''*, adapted to engage the front surface of the lug *f* on the firing-pin to such an extent as to enable the firing-pin to be first cocked and then released by the said arm when the trigger is pulled. At the rear of the lug *f* the firing-pin *d* is provided with a spring-pressed pawl *g*, the purpose of which will be hereinafter set forth.

The device operates in the following manner: Assuming the parts to be in the position shown in Fig. 1, on pulling the trigger *a* the

sear *b* will, with its arm *b''*, force the firing-pin *d* back to the "full-cock," and then when the parts have attained the position indicated in Fig. 2 release the same, allowing the weapon to be discharged. In the ordinary course of events the recoil would throw the pin back, with its lug *f*, to the rear of the upper end of the arm *b''* and reset the parts ready for the next operation of the trigger, so that they would occupy the position shown in Fig. 1 after the cartridge had been discharged. The object of the spring-pressed pawl *g* on the firing-pin is to provide for the automatic re-cocking of the weapon if a cartridge hangs fire. In this case there would be no recoil, and after the trigger had been pulled and released the parts would occupy the position shown in Fig. 3, with the arm *b''* of the sear at the rear of the lug *f* of the firing-pin. If the trigger is pulled again, immediately the arm *b''* will now engage the end of the spring-pressed pawl *g* and will automatically re-cock the firing-pin and again discharge the weapon. This operation may be repeated until the cartridge has been discharged, whereas it has hitherto been necessary in such cases to first recock the hammer or firing-pin by hand.

The construction might be varied in a great many ways without departing from the spirit of the present invention, and the invention may easily be adapted to a great variety of automatic and other firearms.

I claim as my invention—

In a self-cocking mechanism for automatic firearms, the combination of a lug on the firing-pin and an arm on the sear, the two parts engaging sufficiently long to enable the firing-pin to be cocked and released by a single pull on the trigger and a spring-pressed pawl to the rear of the lug on the firing-pin to engage the arm *b''* of the sear, when the weapon hangs fire substantially as described.

In witness whereof I have hereunto set my hand in presence of two witnesses.

EMIL ROTH.
